(57) **CLAIM**

The ornamental design for a locking pin, as shown and described.

DESCRIPTION

FIG. 1 is a perspective view of a locking pin showing our new design;

FIG. 2 is a top view of the pin shown in FIG. 1;

FIG. 3 is a front view of the pin shown in FIG. 1 wherein the rear view is a mirror image of the front view;

FIG. 4 is a right side view of the pin shown in FIG. 1 wherein the left side view is a mirror image of the right side view; and,

FIG. 5 is a bottom view of the pin shown in FIG. 1.

The broken lines are for illustrative purposes only and form no part of the claimed design.
